Patented July 5, 1921.

UNITED STATES PATENT OFFICE.

GEORGE W. MATTERN, OF DAYTON, OHIO, ASSIGNOR TO THE CRAWFORD, McGREGOR AND CANBY COMPANY, OF DAYTON, OHIO, A CORPORATION OF OHIO.

GOLF-CLUB.

1,383,654.

Specification of Letters Patent.

Patented July 5, 1921.

Application filed August 12, 1919. Serial No. 316,956.

To all whom it may concern:

Be it known that I, GEORGE W. MATTERN, a citizen of the United States, residing at Dayton, in the county of Montgomery and 5 State of Ohio, have invented certain new and useful Improvements in Golf-Clubs, of which the following is a specification.

My invention relates to golf clubs, and more particularly to a reinforced striking 20 face therefor.

The object of the invention is to simplify the structure as well as the means and mode of reinforcing golf club heads, whereby they may not only be economically manufactured, 15 but will be more efficient in use, and lively in action affording long distance flights of the ball, and unlikely to get out of repair.

A further object of the invention is to provide improved means for anchoring both the 20 inserted face plate of the club head, and an inserted impact plug embedded in the striking face.

A further object of the invention is to provide a series of impact plugs embedded 25 in the striking face, in such relation one with the other, as to afford a substantially uniform or equalized action over a comparatively large area thus to some extent compensating for some inaccuracies of the player's stroke.

A further object of the invention is to provide means for overcoming disadvantages due to expansion and contraction of the inserted body.

35 With the above primary and other incidental objects in view, as will more fully appear in the specification, the invention consists of the features of construction, the parts, and combinations thereof, and the 40 mode of operation or their equivalents as hereinafter described and set forth in the claims.

Referring to the drawings, Figure 1 is a perspective view of a head of a golf club 45 to which the present invention has been applied. Fig. 2 is a bottom sectional plan view substantially on line 2—2 of Fig. 1. Fig. 3 is a perspective view of a modification of the construction shown in Figs. 1 and 2. Fig. 4 is a detailed sectional view substantially on line 4—4 of Fig. 3. Fig. 5 is a detail perspective view of the insert materials prior to being assembled. Fig. 6 is a perspective view of the assembled insert 55 materials before being separated into sec-

tions of proper lengths. Fig. 7 is a detailed perspective view of one of the insert sections prepared for embedding in the head of the club.

Like parts are indicated by similar characters of reference throughout the several views.

The invention herein shown and described is particularly adapted for embodiment in drivers and brassies. In the drawings there 65 is shown a club of which 1 is the head and 2 the usual handle shaft. It has long been the practice to provide the striking face 3 of the head 1 with an inserted face plate 4 of fiber or some similar material. Such face 70 plate 4 has usually been cemented or glued in the recess or mortise of the head 1, and further secured by a series of dowel pins inserted through the face plate 4 into the head 1. In the present instance in lieu of 75 extending the dowels through the face plate 4, there are provided diagonally disposed dowel pins 5, located coincident with the edge of the face plate 4, which intersect the margin of the face plate and slightly over- 80 hang the same as shown in Fig. 2. These diagonal or inclined dowel pins 5 serve to securely lock the face plate 4 in position without interfering with the insertion of the impact plug hereafter referred to. 85

In order to provide a quick acting solid striking surface which will give "distance" to the ball an impact plug 6 of ivory or other material possessing the desired characteristics is embedded in the face of the 90 head 1. While ivory is a most desirable material so far as its action upon the ball is concerned, it possesses the disadvantage of a wide range of expansion and contraction under varying climatic and temperature conditions. As a result of the high factor of expansion and contraction, attempts to cement an ivory impact plug in the head 1 of the club has not been entirely successful. The 100 contraction of the plug under such conditions causes it to be loosened in its seat or socket and eventually entirely disengaged from the club. To overcome this difficulty in the present construction, the impact plug 6 of ivory or other suitable material is positively locked or anchored in its adjusted position. To this end the impact plug 6 before being positioned in the head, is incased in a sleeve 7 of material possessing a low 105 factor of expansion and contraction, such as 110

fiber, composition, or other suitable material, to which the impact plug 6 is positively secured and locked by means of a transverse pin 8 which passes diametrically through the plug 6 and inclosing sleeve 7.

5 In preparing these inserts the preferred method, though not necessarily the essential or only process, consists in providing short lengths of the insert or plug material, after 10 being turned to proper gage, and like lengths of fiber tubing as shown at 9 and 10 respectively in Fig. 5. The tubing and insert or core are accurately sized or proportioned to closely fit each other. The exterior surface of the core or insert 9 is 15 slightly roughened or scored as is also the interior surface of the tube 10. The core or insert 9 after being coated with a waterproof adhesive cement is pressed or driven 20 tightly within the tube 10. Transverse holes are then drilled diametrically through the tube 10 and the inclosed core or insert 9 at measured intervals as indicated in Fig. 6. The transverse locking pins 8 are then 25 inserted through these holes and the ends of the pins are upset or riveted and subsequently dressed off flush with the periphery of the tube 10. To relieve any stress or strain upon the parts and to obviate the 30 danger of splitting the insert core 9, the transverse holes for the pins 8 are preferably though not necessarily drilled on alternating diameters, as indicated in Fig. 6. After the insert core 9 is cemented within 35 the tube 10 and locked by the transverse pins 8, this assembled body is severed into sections as shown in Fig. 7 by sawing it transversely between the pins 8. Each of the sections so formed comprises an impact 40 plug or insert for a golf club head. The head 1 is prepared to receive such inserts by being thoroughly dried in a dry kiln or oven, until substantially all moisture is evaporated therefrom. While in this dry 45 condition a hole is bored through the face plate 4 into the head 1 to receive the impact plug or insert. It may be here stated that the face plate 4 and dowel pins 5 are preferably not fitted to the head until after 50 it has been dried as before mentioned. The periphery of the insert or impact plug as shown in Fig. 7 is then slightly roughened and coated with a waterproof adhesive cement, and is driven firmly within the hole 55 or socket in the kiln dried head 1. The club head 1 upon removal from the dry kiln, almost immediately begins to absorb moisture from the atmosphere which tends to swell the wood causing it to contract upon 60 the inserted impact plug. The sleeve 7, whether of fiber or other material possesses a low factor of expansion and contraction, and is not materially effected by either excessive moisture or the lack thereof. Having 65 been accurately fitted to a thoroughly

dried head 1, there is little or no tendency for the sleeve 7 to become loosened by changes of humidity or temperature. The plug 6 being firmly and positively locked in engagement with the sleeve 7 by means of the transverse pins 8, cannot become disengaged from the head regardless of any relative expansion or contraction of the parts. By this means the disadvantage of a loose insert is overcome.

75

In Fig. 1 the head has been shown provided with a single impact plug or insert of comparatively large size. To meet with the peculiarities of plays, strokes, and idiosyncrasies of individual players as well as to 80 compensate somewhat for inaccuracies of their stroke by providing a more extended striking area, there is shown in Fig. 3 a modification of the construction shown in Fig. 1, in which six impact plugs constructed 85 as heretofore described, are provided in a single striking face. While six such impact plugs is a convenient number, it is to be understood that the series may be varied in extent and arrangement. However, the 90 arrangement shown in Fig. 3 has been found quite efficient and desirable. This arrangement of impact plugs consists of a central plug positioned somewhat below the center of the striking face, around which is 95 arranged a series of plugs of smaller diameter, positioned in different radial relations with the central larger plug. The arrangement is such that if the player through inaccuracy of stroke fails to engage the ball 100 fairly upon the central larger impact plug, he can hardly fail to engage it with one of the smaller adjacent impact plugs, and thus although not possessing the skill of the expert, he achieves to a very great degree the 105 same advantage as does the more expert player with the single impact plug, shown in Fig. 1.

While the locking dowels 5 shown in Figs. 1 and 2 may be also employed in a construction shown in Fig. 3 as indicated by dotted lines therein, it is possible to achieve a similar result by arranging the outer series of impact plugs in diagonal or inclined relation as shown at 11 in Fig. 4. As shown 115 in Fig. 4, impact plugs themselves achieve the same locking function as the dowels 5. It is to be understood that the sleeve and core of each of the impact plugs shown in Fig. 3, are interlocked by the transverse 120 pins 8 as before described.

This inclined relation of the inserts or impact plugs, in relation one with the other has a three fold purpose. It affords a dove-tailed or locking effect to secure the face 125 plate immovably in position. It will be obvious that the face plate cannot be withdrawn without further removing the diagonally disposed inserts or impact plugs. A further object achieved by this inclined or 130

diagonal relation of the inserts is the wider distribution of the vibration and force of impact to the head. The insert plugs extending in various directions radiating substantially from the point of impact, transmit the vibrations or force of the impact substantially in the line of their length, and thus distribute or diffuse the force of the blow throughout the head of the plug. Another, 10 none the less important feature of this construction is increased strength of the club, by affording more material of the club head between the several inserts. In other words the material is not removed wholly in a concentrated locality, or one hole bored quite closely to the other, as would be necessary in parallel arrangement of the inserts. By spreading the inserts more material is left between the insert receiving holes, or sockets, 15 and hence the head is materially strengthened.

From the above description it will be apparent that there is thus provided a device of the character described possessing the 25 particular features of advantage before enumerated as desirable, but which obviously is susceptible of modification in its form, proportions, detail construction and arrangement of parts without departing from the 30 principle involved or sacrificing any of its advantages.

While in order to comply with the statute the invention has been described in language more or less specific as to structural features, 35 it is to be understood that the invention is not limited to the specific details shown, but that the means and construction herein disclosed comprise but one of several modes of putting the invention into effect, and the 40 invention is therefore claimed in any of its forms or modifications within the legitimate and valid scope of the appended claims.

Having thus described my invention, I claim:

1. The combination with a golf club of a 45 body of ivory, and a sleeve of fiber inclosing the body of ivory, said body and inclosing sleeve being embedded in the striking face of the club, substantially as specified.

2. The combination with a golf club of a 50 body of ivory, a sleeve of fiber inclosing the body of ivory and a transverse pin transfixing the sleeve and body, said sleeve and inclosed body being embedded in the striking 55 face of the club.

3. The combination with a golf club, of an 60 insert stationarily embedded in the striking face of the club and a sleeve of characteristically different material also stationarily embedded therein and surrounding the insert.

4. The combination with a golf club of a 65 two concentric bodies of characteristically different materials stationarily embedded in the striking face of the club.

5. The combination with a golf club of an

insert embedded in the striking face of the club, a sleeve of characteristically different material surrounding the insert and means positively engaging the insert and sleeve one, 70 with the other.

6. The combination with a golf club of two concentric bodies of characteristically different material positively locked in engagement one with the other, said interlocked bodies being embedded in the striking 75 face of the club.

7. The combination with a golf club of a plurality of inserts embedded in the striking face of the club, each insert comprising a 80 plurality of concentric bodies, the axes of said inserts being inclined in relation one with the other.

8. The herein described method of affixing inserts in golf club heads, comprising, incasing the insert in a tubular sleeve, pinning the 85 insert and sleeve by a transverse pin extending therethrough, drying the head of the golf club, forming in the dried head a socket to receive the incased insert, and embedding the same therein.

9. The herein described method of affixing inserts in golf club heads comprising incasing the insert in a tubular sleeve, passing a retaining pin transversely through the sleeve and insert, and securing said sleeve within 95 and to the carrying body.

10. The combination with a golf club of an inlaid face plate in the striking surface of the club, and diagonally disposed dowel pins 100 also inserted in the striking surface and intersecting the marginal edges of the face plate.

11. The combination with a golf club of an insert embedded in the striking face of the club, a second insert embedded in the striking 105 face of the club and surrounding the first mentioned insert, and a face plate likewise embedded in the striking face of the club and surrounding both said inserts.

12. The combination with a golf club of a 110 plurality of solid inserts permanently embedded in the striking face of the club, each insert comprising a plurality of concentric bodies, substantially as specified.

13. The combination with a golf club of a 115 plurality of nonintersecting inserts embedded in the striking face thereof in grouped relation wherein one of said inserts is embedded at substantially the normal striking point, the remaining inserts of the 120 group being positioned in a series concentrically arranged in relation with the first mentioned insert, and adjacent thereto.

14. The combination with a golf club of a 125 plurality of inserts embedded in the striking face thereof and spaced one from the other in grouped relation wherein a plurality of said inserts are positioned in an arcuate series substantially concentric in relation with a single insert of the group.

- 15: The combination with a golf club of a plurality of inserts embedded in the striking face thereof in an arcuate series and an additional insert located within the arcuate series 5 of inserts and substantially concentric with the arcuate grouping of the first mentioned inserts.
16. The combination with a golf club of a circular insert located in the striking face 10 thereof, and a series of additional circular inserts of lesser size grouped about the first mentioned insert extending in substantially tangential relation therewith.
17. The combination with a golf club, of 15 an inlaid face plate in the striking surface of the club, and diagonally disposed retain-
- ing studs inserted in the striking surface of the club, in planes substantially perpendicular to the plane of the inlaid face plate, said studs being so positioned as to overhang the 20 marginal edges of said plate.
18. The combination with a golf club, of a plurality of inserts embedded in the striking face of the club, said inserts being inclined in relation one with another, substantially as 25 and for the purpose specified.

In testimony whereof, I have hereunto set my hand this 6th day of August A. D. 1919.

GEORGE W. MATTERN.
